FLUID OPERABLE CONTROL DEVICE

Rankin J. Bush, Jeannette, Pa., assignor to The Westinghouse Air Brake Company, Wilmerding, Pa., a corporation of Pennsylvania

Application September 29, 1944, Serial No. 556,406

9 Claims. (Cl. 121—41)

1

This invention relates to control devices and more particularly to the type adapted to be controlled and operated by fluid under pressure.

In my copending application Serial No. 480,161, filed March 23, 1943, and assigned to the assignee of the present application, there is disclosed a fluid pressure control system for controlling a plurality of internal combustion engines, such as employed for propelling an airplane. This system embodies a plurality of fluid motors for each engine, one motor for controlling the engine speed, another the richness of the fuel mixture supplied to the engine, another for controlling the temperature of the mixture, and still another for controlling the operation of a blower or super-charger.

One object of the invention is the provision of an improved fluid motor for controlling operations such as above described.

Another object of the invention is the provision of an improved fluid motor embodying fluid pressure adjustable pilot means and power means adapted to be operated by fluid under pressure for adjusting the device being controlled, the pilot and power means cooperating to insure positive operation of the power means and thereby by adjustment of the device in accordance with the adjustment of the pilot means.

Another object of the invention is the provision of a motor such as above described arranged to employ a single pipe for controlling operation of the pilot means and for providing fluid under pressure for controlling operation of the power means, so as to maintain at a minimum the weight of the apparatus.

Another object of the invention is the provision of a fluid motor such as above defined which is so constructed as to render the pilot portion very sensitive to and adjustable in accordance with slight changes in a controlling fluid pressure, and which also renders the power means accurately and positively adjustable in accordance with the adjustments of the pilot portion.

Another object of the invention is the provision of a fluid motor of the above type which is relatively small in size, compact and simple in construction, and light in weight for the purpose intended.

Other objects and advantages will be apparent from the following more detailed description of the invention.

In the accompanying drawings:

Fig. 1 is a longitudinal sectional view, partly in diagrammatic form, of one embodiment of the

2

invention; and Fig. 2 is a view similar to Fig. 1 of a modified form of the invention.

Description, Fig. 1

5 The improved fluid motor shown in Fig. 1 of the drawings comprises a hollow casing section 1 open at one end and having at the opposite end a wall 2 and a sleeve 3 carried by said wall and extending centrally into a cylindrical chamber 4 formed within said casing section 1, and thereby of chamber 4, is closed by a cover 5 secured to the casing section 1 by securing means 6, and clamped around its peripheral edge between said cover and casing section is a flexible diaphragm 7.

One side of diaphragm 7 is subject to pressure of fluid in chamber 4 which is open to a fluid pressure release pipe 8. The pipe 8 may lead directly to atmosphere, or it may lead to a so-called sump reservoir (not shown) which is used in connection with certain fluid pressure control systems for receiving fluid under pressure after it has been used to effect a desired operation. In such systems the fluid pressure released to the sump reservoir is recompressed for reuse. This is immaterial to the present invention and no further description of the sump reservoir for its function is therefore necessary, although if desired, reference may be made to my copending application hereinbefore referred to for a complete disclosure of a fluid pressure control system embodying a sump reservoir such as above mentioned.

At the opposite side of diaphragm 7, and thus 35 between said diaphragm and the cover 5, is a fluid pressure control chamber 9 which is connected through a port 10 to a cavity 11 in said cover. The cavity 11 is open through an air strainer 12 to a pipe 13 which is connected to the 40 cover. The pipe 13 constitutes a combined control pipe and fluid pressure supply pipe, as will be more clearly brought out hereinafter.

The fluid motor further comprises a power cylinder portion 14 which is secured by securing means 15 to the opposite end of casing section 1, that is, to the end wall 2, a sealing gasket 16 being clamped between the two parts to prevent leakage of fluid under pressure through the joint. This portion 14 and the cover 5 are provided with bosses 17 for contact with a mounting plate of the like (not shown) and said bosses have screw-threaded bores 18 for receiving the threaded portions of cap screws or the like (not shown) to secure the motor in a desired location or position. 50 The power cylinder 14 contains a differential

area piston means 19, which for the purpose of illustration only, may comprise two axially arranged, spaced apart and connected piston heads 20 and 21; the piston head 20 being of greater diameter than the piston head 21. These piston heads are slidably mounted in suitable bores in the power cylinder 14 and each head is provided with a ring groove in which there is disposed a ring 22 having sealing and sliding contact with the wall of the respective bore.

One end of the bore in which the larger piston head 20 is disposed is closed by wall 2 of the casing section 1, and said wall together with the adjacent face of the piston head form a fluid pressure control chamber 23. The opposite end of the bore, in which the piston head 21 is mounted, is closed by an end wall 24 of the power cylinder 14 and between said end wall and the adjacent face of the piston head is a chamber 25 which is open to atmosphere through a port 26. Between the two piston heads 20 and 21 is a dash-pot chamber 27 which is in constant communication with the combined control and fluid pressure supply pipe 13 by way of a passage 28, containing a choke 28a, a passage 29, a pipe 30, and a passage 31 in the cover 5, leading to cavity 11 which is connected to pipe 13. It will be noted that the opposite ends of pipe 30 are, respectively, disposed in recesses in the cover 5 and cylinder portion 14, and are engaged by sealing rings 32 to prevent leakage of fluid under pressure from said pipe to atmosphere.

The piston means 19 is arranged in coaxial relation to the opening through sleeve 3, which opening is lined for a portion of its length adjacent its inner end with a wear bushing 33. The piston means 19 has a stem 34 projecting therefrom through the sleeve 3 and bushing 33. Within the bushing 33 the stem 34 has a piston portion 35 of substantially the same diameter as the bore of the bushing and this piston portion carries a ring 36 having sealing and sliding contact with the inner wall of said bushing. At both sides of the piston portion 35, the stem 34 is of smaller diameter than the bore in bushing 33, and this provides, at the side adjacent piston means 19, an annular space 37 around the stem 34, which space leads and opens to the fluid pressure control chamber 23.

A rod or stem 38 arranged opposite the stem 34 projects from the piston means 19 through chamber 25 and a bore in a boss 39 projecting from the outer face of the end wall 24 of the cylinder portion 14 of the casing. In the boss 39, adjacent its outer end, is a wear bushing 40 in which the rod 38 is slidably mounted and supported. Adjacent the inner end of bushing 40 is a ring 41 secured in boss 39 and having sealing and sliding contact with piston rod 38. Between the ring 41 and the bushing 40 there is a groove 42 encircling the rod 38 and adapted to carry lubricant for lubricating said rod. The means by which groove 42 is filled with lubricant is not shown in the drawings and is immaterial to the invention. At the opposite end of bushing 40 is a ring 43 having sealing and sliding contact with the piston rod 38 and this ring is held in place in boss 39 by any suitable securing means, such as a snap ring 44. The two rings 41 and 43 act to prevent leakage of lubricant along the piston rod from groove 42, as will be obvious.

The piston rod 38 also projects through an opening provided in a boss 45 extending into chamber 25 from the end wall 24 of the cylinder portion 14. Adjacent its inner end the boss 45

is in substantial contact with the peripheral surface of rod 38 and is provided with an annular groove in which there is disposed a ring 46 having sealing and sliding contact with the rod. Between the sealing ring 46 and the sealing ring 41, the boss 45 has a recess or chamber 47 encircling the rod 38 and to which is open or connected the passage 29, which, as before described, is open to the combined control and fluid pressure supply pipe 13. The sealing rings 41 and 46 are provided to prevent leakage of fluid under pressure in either direction along the rod 38 from chamber 47.

Beyond the end of boss 39, the end of the piston rod 38 is disposed in a slot 50 provided in an operating lever 48 between the ends of said lever, said rod being operatively connected to said lever by a pin 49 extending through aligned openings in said stem and the opposite side walls of slot 50.

The lever 48 has at one end a rib 51 provided with a surface 52 arranged generally parallel to the length of the lever and at an angle to the axis of the piston rod 38. A fulcrum member 53 is mounted against this surface 52 and has a stud 54 extending through a slot 55 in rib 51, said slot extending parallel to the length of the lever. A lock nut 56 on stud 55 is provided to contact the side of rib 51 opposite surface 52 to secure member 53 in an adjusted position with respect to said surface. Release of nut 56 from rib 51 will permit adjustment of member 53 on surface 52, as will be apparent.

For adjusting the fulcrum member 53 along the surface 52, an adjusting screw 57, extending parallel to the length of the lever and through a bore in said member, has screw-threaded engagement with said member. This adjusting screw extends through a slot 58 provided in a rib 59 extending from the rib 51. On the outer end of screw 57 is a head 60 engaging the outer surface of rib 59. The head 60 is provided with a slot 61 to receive a screw driver for turning the screw. Adjacent the inner surface of rib 59, a washer 62 is disposed in an annular groove in the screw 57, said washer and the screw head 60 being thus arranged to cooperate with the rib 59 to hold the screw 57 against longitudinal movement relative to the lever, whereby the member 53 may be adjusted either toward or away from the piston rod 38 by turning the screw 60. Turning the lock nut 56 against rib 51 will lock the member 53 in an adjusted position.

The member 53 is connected by a pivot pin 63 to one end of a link 64, the opposite end of which link is mounted to turn on a pin 65 secured in an ear 66 projecting from the cylinder portion 14 of the motor.

The opposite end of lever 48 is adapted to be connected to a device which it is desired to operate and for this purpose may be provided with one or more openings 67 either one of which is adapted to receive a connecting pin of the like.

Between the holes 67 and operating pin 49 the lever is provided with a bore in which is mounted an adjusting screw 68 having screw threaded engagement with the wall of said bore. The inner end of screw 68 engages a shoulder 69 on the cylinder portion 14 of the motor, while in the outer end is a slot 70 for receiving a screw driver whereby the screw may be turned. A lock nut 71 on the screw 68 is provided to engage the lever to lock said screw in an adjusted condition.

Disposed in chamber 4 is a diaphragm follower 73 comprising a central cylindrical portion 74 which at the end opposite the diaphragm 7 is

provided with an annular inturned flange 75, and an annular outturned flange 76. A coil regulating spring 77 contained in chamber 4 and encircling the sleeve 3 projecting from end wall 2 of the casing section 1, has one end bearing against said wall and the opposite end bearing against the flange 76. This spring is under pressure, for reasons which will be later brought out.

The end of the cylindrical portion 74 of follower 73, adjacent to diaphragm 7, is closed by a cap 78 having as its center an aperture, and freely extending through this aperture into a chamber 79 formed within said cylindrical portion is a boss 80 which is formed integral with the diaphragm 7. The diaphragm and boss 80 are both preferably made of a resilient material, such as a rubber composition.

The diaphragm 7 comprises a central portion engaging the cap 78, an annular clamping flange 81 disposed between the casing section 1 and cover 5 as before mentioned, and a connecting annular corrugation 82 the inner wall of which is telescoped over the central portion 74 of the follower 73 for supporting said follower. In this supported relation of the diaphragm follower 74 relative to the diaphragm, the boss 80 is free of contact with the cap 78.

A boss 83 projecting into chamber 9 from cover 5 is provided for contact by diaphragm 7 to limit deflection of said diaphragm in the direction of said cover by spring 77. A rib 84 projecting from wall 2 of the casing section 1 into chamber 23 is provided for contact by piston means 19 to limit movement of said piston means in the same direction.

A valve member 85 contained in chamber 4 has a collar 86 engaging the end of the piston stem 34, and also has a portion 87 extending into a bore in said stem. Adjacent collar 86 the portion 87 is provided with screw threads cooperating with threads in the stem 34 to secure the member 85 to said stem. Beyond this screw-threaded portion of member 85 the stem 34 is provided with an annular recess 88 encircling said member and connected by port 89 to the annular space 37 which encircles the stem 34 and which is open to the control chamber 23 at the right hand face of the piston head 20. The port 89 is of relatively small size and acts in the capacity of a choke and may hereinafter be referred to as choke 89.

The piston stem 34 has a chamber 90, one end of which is formed by the end of the portion 87 of the valve member 85. Leakage of fluid under pressure between chamber 90 and recess 88 is prevented by a ring 91 carried in a recess in stem 34 and engaging the peripheral surface of said portion 87. The chamber 90 is in constant communication with the control and fluid pressure supply pipe 13 by way of an axial bore 92 extending through the piston means 19 and into the piston stem 38 where it is connected by a radial port 93 to the annular recess 47 encircling said stem.

The valve member 85 also has a part 94 extending into chamber 79 in the cylindrical portion 74 of the diaphragm follower 73. In chamber 79 the part 94 is provided with an annular collar 95 which is of greater diameter than the opening through flange 75 on the diaphragm follower and which is adapted to be engaged by said flange under a condition to be later described.

The valve member 85 has an axial bore which opens at one end to chamber 90 through a valve seat provided for engagement by a fluid pressure supply valve 96 contained in said chamber, and

which opens at the opposite end through the bottom wall of a counter bore provided in the part 94 of said member. Slidably mounted in this counter bore is a cup shaped retainer 97 having a bore through its closed end aligned with the bore in member 85. Extending through this bore in retainer 97 and into the bore in valve member 85 is a sleeve 98 adapted to reciprocate in said bores. The sleeve 98 has an enlargement or head 99 partially contained within the retainer 97 and adapted to be engaged by boss 89 projecting from the diaphragm. Encircling the head 99 is an annular collar 100, and interposed between this collar and the closed end of the retainer 97 is a coil spring 101 which encircles said head and is under compression. One purpose of this spring is to urge the retainer 97 against one side of a sealing ring 102, which is contained in a recess in valve member 85 encircling the sleeve 98, for thereby forcing said ring into sealing and sliding contact with said sleeve to prevent leakage of fluid under pressure from the inner end of said sleeve along the outer surface of said sleeve and past said retainer to chamber 4.

The sleeve 98 has an axial bore 103, one end of which is connected within the head 99 to a relatively small port or choke 104 which opens to chamber 79 within the diaphragm follower 74 and thus to chamber 4 and the fluid pressure release pipe 8. The opposite end of bore 103 opens through a valve seat on the opposite end of the sleeve to the axial bore in valve member 85, and slidably mounted in said axial bore is a pin 105 having on one end a release valve 106 disposed for engaging said valve seat. The pin 105 is integrally connected by a fluted stem 107 to the supply valve 96. The fluted stem 107 has sliding contact with the wall of the bore in which it is disposed, while the pin 105 is of smaller diameter than said bore. Between the supply valve 96 and release valve 106, the axial bore in the valve member 85 is connected by a radial port 108 to the annular recess 88 encircling said member.

A spring seat 109 is disposed in the supply valve 45 chamber 90 against a shoulder formed at the junction of said chamber and bore 92, and interposed between and engaging at opposite ends said seat and the supply valve 96 is a coil spring 110. This spring is under pressure and constantly effective to urge the supply valve 96 and release valve 106 in the direction of their seats. The spring seat 109 is provided with a bore 111 connecting the supply valve chamber 90 to bore 92.

Adjustments, Fig. 1

Assuming that the pressure of the fluid at the source (not shown) for supply through pipe 13 to the fluid motor is 150 pounds and that the desired range of variation in pressure of fluid for controlling operation of said motor is seventy pounds, the difference, or eighty pounds, may be the minimum pressure, or what may be considered as the normal pressure, provided in pipe 13 to the motor by operation of an operator's control device (not shown).

This normal pressure of fluid in pipe 13 will equalize through port 10 into diaphragm chamber 9, and also through port 31, pipe 30, passages 29 and 28 and choke 28a into the dash-pot chamber 27 between the two piston heads 20 and 21, and will also equalize into the supply valve chamber 90 from passage 29 by way of annular chamber 47 encircling the piston rod 38 and port 93 and bore 92 in said rod.

The normal pressure of eighty pounds effective

in diaphragm chamber 9 on the diaphragm 82 will deflect said diaphragm against the opposing pressure of spring 77 until the pressure of said spring is increased to a degree to balance the opposing pressure of fluid on the diaphragm, whereupon movement of the diaphragm will cease. This movement of the diaphragm, and its normal position in which its movement ceases, will therefore depend upon the pickup in force characteristic of spring 77. It will be assumed that this normal position of the diaphragm is the position in which it is shown in the drawings, but it will be understood that for different springs 77 the normal position may be either slightly to one side or the other of the position in which the diaphragm is shown in the drawings.

The normal pressure of fluid effective in the dash-pot chamber 27 between the piston heads 20 and 21 produces a force, equal to said pressure times the difference in areas of the two piston heads, and this force acts to move the piston means 19 and all parts secured thereto or carried thereby in the direction of the right hand. The adjusting screw 68 may initially be backed out of the lever 48 sufficiently to permit the piston means 19 to move the head 99 on the release valve sleeve 98 into contact with boss 80 on the diaphragm 7 and to then move the valve member 85 relative to said sleeve. As the valve member 85 is thus moved relative to sleeve 98 the release valve 106 will be moved by spring 110 into seating engagement with the end of the sleeve 98. The sleeve 98, being held against movement by contact with the diaphragm boss 80, will then hold the release valve 106, as well as the supply valve 96, against further movement with valve member 85. As a result, the continued movement of the piston means 19 and valve member 85 by pressure of fluid in dash-pot chamber 27 will move said member out of seating engagement with the fluid pressure supply valve 96.

When the supply valve 96 is thus opened, fluid under pressure, supplied to the supply valve chamber 90 from pipe 13, will then flow past said valve and through ports 103 and 89 to chamber 23 at the right hand face of the larger piston head 20 and therein produce a force against said head which acts in opposition to the opposing force created by pressure of fluid in chamber 27 between the two piston heads. Fluid under pressure will thus continue to be supplied to chamber 23 until the force created thereby, slightly exceeds the opposing force created by pressure of fluid in chamber 27 whereupon the piston means 19 will start to move in the direction of the left hand and will continue such movement until the valve member 85 seats against the supply valve 96 and prevents further flow of fluid under pressure to chamber 23. When the supply of fluid under pressure to chamber 23 is thus cut off, it will be noted that the piston means 19 will cease moving in a position in which both the supply and release valves will be closed, and fluid at some pressure, such as forty pounds, will be effective in chamber 23 balancing the opposing pressure of fluid in chamber 27 on piston means 19.

After the piston means 19 attains the normal position determined by the minimum pressure of fluid (eighty pounds) in pipe 13, the screw 68 is then turned into contact with shoulder 69 on the casing which thereafter will define the normal position of lever 48.

The pressure pickup characteristic of spring 77 determines the extent of deflection of diaphragm 7, as above mentioned. It will therefore be ap-

parent that when said diaphragm is subjected to a maximum pressure, the extent of deflection of said diaphragm from its normal position will be less if the pickup of the spring 77 is relatively great than if the pickup is less. The movement of piston means 19 corresponds to the deflection of the diaphragm, as will hereinafter be brought out, and thus also depends upon the pickup of control spring 77.

10 Regardless of the pressure increase or pickup characteristic of spring 77 however, it is desired to provide a certain range of movement of the operating lever 48, at either one or the other of the openings 67 to which the device to be controlled will be connected, and this is obtained by adjustment of the lever fulcrum member 53 relative to the lever 48 by means of the screw 57. For instance, if the pickup of spring 77 is relatively great, thereby limiting the deflection of diaphragm 7, the fulcrum member 53 will be adjusted toward the pin 49 to increase the movement of the lever at the one or other opening 67. On the other hand, if the pickup of the spring is less, so that the diaphragm 7 will be deflected to a greater extent for a certain change in pressure of fluid in chamber 9, the fulcrum member 53 will be adjusted away from pin 49 to reduce the movement of lever 48.

15 It will now be seen that the pickup characteristic of spring 77 determines the normal position of diaphragm 7 and thereby of piston means 19 and lever 48, while adjustment of the lever fulcrum member 53 relative to said lever provides for obtaining a chosen degree of movement of said lever, at the point where it will be connected to the device being controlled. Let it be assumed that the desired range of movement of lever 48 is between the position in which it is shown in the drawing and a position such as indicated by 20 a dot and dash line designated by reference numeral 112, and that the fulcrum member 53 is adjusted to provide for such movement.

25 After the motor is adjusted as above described, it will then be connected to the device (not shown) to be controlled. It will also be connected for control to an operator's control valve or the like (not shown) which may be located at a remote station and which may be manually operative to vary the pressure of fluid in chamber 9 between limits such as eighty and one hundred and fifty pounds, above mentioned.

Operation, Fig. 1

30 With fluid at the minimum or normal pressure of eighty pounds present in pipe 13, all parts of the fluid motor will assume the positions in which they are shown in Fig. 1 of the drawings as will be evident from the above description.

35 If the operator now desires to rock lever 48 out of its normal position in a clockwise direction as viewed in the drawings, he will increase the pressure of fluid in pipe 13 by an amount corresponding to the desired extent of such movement. This increase in pressure being effective in chamber 9 on diaphragm 7 will deflect said diaphragm against the opposing pressure of spring 77 to a position in which the pressure of said spring becomes increased to a degree which balances the pressure of fluid in chamber 9 and in which position deflection of the diaphragm will cease.

40 This deflection of diaphragm 7 against the opposing pressure of spring 77 will act through the head 99 of sleeve 98 to move said sleeve into the valve member 85, and with the release valve 106

normally seated, this movement will act through said valve to open the supply valve 96.

When the supply valve 96 is opened, fluid under pressure supplied from the supply pipe 13 to the supply valve chamber 90, will flow past said valve and through ports 108 and 89 to chamber 23 at the right hand face of the piston head 29 to increase the pressure in said chamber over the normal pressure therein. When the pressure of fluid in chamber 23 is thus sufficiently increased with respect to the opposing pressure of fluid in dash-pot chamber 27, piston means 19 will move in the direction of the left hand and thereby rock lever 43 in a clockwise direction out of its normal position.

The piston means 19 may start moving, as just described, before the diaphragm 7 obtains the position in which it stops. After movement of the diaphragm 7 ceases however, the continued movement of piston means 19 and valve member 85 will be relative to the supply valve 96 until said member contacts the supply valve and prevents further supply of fluid under pressure to chamber 23, whereupon movement of the piston means 19 will promptly cease for reasons which will hereinafter be described.

If the operator now desires to move the lever 43 further in a clockwise direction from normal position, he will increase the pressure of fluid in pipe 13 by an amount corresponding to the degree of desired movement, and the motor will again operate as above described to rock lever 43 to the desired position. The pressure of fluid in pipe 13 may thus be increased in any desired increments, up to the maximum degree of one hundred fifty pounds, or it may be increased in a single or continuous step to the maximum pressure, and the motor will correspondingly operate to position lever 43, said lever being moved to the position indicated by the dot and dash line 112 when the maximum pressure of one hundred fifty pounds is provided in the control pipe 13.

From the above described operation it will be seen that the diaphragm 7, the release valve 106 and the supply valve 96, which constitute the pilot portion of the motor, are positioned directly by and in accordance with the increase in pressure of fluid in pipe 13, whereas the piston means 19, constituting the power portion of the motor, is positioned in accordance with the position of the diaphragm 7.

The movement of piston means 19 to any selected position may require an increase in pressure of fluid in chamber 23 greater or less than the increase in pressure in pipe 13, depending mainly upon the resistance to movement of the device being controlled. The pipe 13 being provided with fluid under pressure in excess of eighty pounds, depending upon the increase in such pressure over the normal degree for controlling the motor, constitutes a source of fluid at a pressure sufficiently in excess of the normal pressure of around forty pounds in chamber 23 to ensure obtaining adequate force on the piston means 19 for operating a device having a maximum degree of resistance to movement, as will be apparent.

As above mentioned, the piston means 19 will move to and stop in a position corresponding to the pressure of fluid in chamber 9 and hence corresponding to the position of diaphragm 7, it being noted that this stopping occurs at the instant of closure of the supply valve 96. The reason for this positive stopping of said piston means in a position corresponding to the position of said diaphragm will now be described.

As before mentioned, the dash-pot chamber 27 is at all times connected to the supply pipe 13 so that the pressure of fluid in said chamber will tend to increase through choke 28a, along with an increase in pressure of fluid in pipe 13, to provide an increase in the force which opposes movement of the piston means 19 by the increase in pressure of fluid in chamber 23. As soon as the piston means 19 starts to move in response to the increase in pressure of fluid in chamber 23, it will be noted that the piston head 29 reduces the volume of chamber 27 and tends to increase the pressure of fluid in said chamber over the supply pipe pressure effective in passage 28, so as to cause an outflow of fluid under pressure from chamber 27 to said passage. Further, the rate of supply of fluid under pressure to and thus the rate of increase in pressure of fluid in chamber 23 is limited by the flow capacity of the small port or choke 89.

If the piston means 19 starts to move upon a relatively small increase in pressure of fluid in chamber 23 under which condition the pressure of fluid in the dash-pot chamber 27 may not increase to any great degree over the supply pressure in pipe 13, it has been found that said piston means will positively stop immediately upon closing of the supply valve due apparently to the combination of factors including the high pressure dash-pot 27 above mentioned. In case however the piston means 19 tends to move suddenly upon an increase in pressure of fluid in chamber 23, due for instance to requiring a relative high force for initiating movement of the device being controlled, or for any other reason, the choke 28a acts to so limit outflow of fluid under pressure from chamber 27, that the piston head 29 will cause the pressure of fluid in said chamber to increase over the supply pressure effective in passage 29 to a degree which will vary in proportion to the rate of such movement, and this increase in pressure in chamber 27 will promptly decelerate or snub the piston means 19 and prevent it over traveling the position in which it is desired it will stop, so that when said position is attained and the supply valve 96 closes, the piston means 19 will positively stop. Promptly upon stopping of the piston means 19 the pressure of fluid in the dash-pot chamber 27 will equalize through choke 28a with that in the supply pipe.

Now assuming that the lever 43 has been moved to the position indicated by the dot and dash line 112, or to any other position out of normal position, if the operator desires to return said lever toward its normal position, in which it is shown in the drawings, he will reduce the pressure of fluid in pipe 13 to a degree corresponding to the desired new position of said lever.

Upon this reduction in pressure in pipe 13 the diaphragm 7 will be deflected by spring 77 in the direction of cover 5 to a position corresponding to the reduced pressure. This deflection of diaphragm 7 will be relative to the piston means 19 and the valve member 85, and spring 101 will maintain the head 99 of sleeve 98 in contact with the diaphragm boss 83 and thus pull said sleeve out of contact with the release valve 106. Fluid under pressure will then be released from chamber 23 past the release valve 106 to bore 103 in said sleeve and thence through the restricted release port or choke 104 to chamber 4 and the release pipe 8.

When the pressure of fluid in pipe 13 is reduced to effect a reduction of pressure in piston

chamber 23 as just described, the pressure in chamber 27 between the piston heads 20 and 21 will start to reduce through choke 28a, but as soon as the pressure in chamber 23 is reduced sufficiently with respect to the pressure in chamber 27 to produce a force on piston means 19 adequate to move said piston means in the direction of the right hand, said piston means will move and draw the lever 48 back towards its normal position, in which it is shown in the drawings.

As the piston means 19 thus moves towards its normal position the volume of dash-pot chamber 27 will increase and thereby tend to reduce the pressure of fluid therein to a degree below the control pipe pressure in passage 28. Thus upon initiating the reduction in pressure in the control pipe 13 there may be a flow of fluid under pressure out of chamber 27 through choke 28a, but this flow will be only momentary and then a reverse flow may occur. The flow capacity of choke 28a is such however that as the piston means 19 moves in response to a reduction in pressure in chamber 23, the pressure in the dash-pot chamber 27 will reduce below that in passage 28 a degree corresponding to the rate of such movement. Thus, if the movement of piston means 19 tends to be rapid the reduction in pressure in chamber 27 will be so great as to promptly snub and decelerate the piston means, whereas in case the movement is at a slower rate, the snubbing action will be of a less degree. There may be substantially no snubbing action in case the rate of movement of piston means 19 is sufficiently slow, as will be apparent.

As the piston means 19 thus moves towards the right hand in response to a reduction in pressure in the control pipe 13 it may initially move with the diaphragm 7 as said diaphragm moves to its new position determined by the reduction in pressure in control pipe 13. After the diaphragm obtains its new position however and stops moving, the movement of piston means 19 will then be relative to said diaphragm and will thus move release valve 106, under the action of spring 110 holding the supply valve 96 seated, in the direction of and finally into contact with its seat in a position of the piston means corresponding to the position of the diaphragm. When the release valve 106 closes as just described, further reduction in pressure in chamber 23 is prevented, whereupon movement of the piston means 19 will stop, thereby stopping the lever 48 in a position corresponding to the position of diaphragm 7 and hence the pressure in pipe 13. The piston means 19 will positively stop upon closing of the release valve 106 as just described, due to the dash-pot action provided by chamber 27 and choke 28a, and the controlled rate of release of fluid under pressure from chamber 23 by the release choke 104, as above described.

If the pressure in the control pipe 13 is further reduced, the motor will operate in the same manner as just described to positively move lever 48 to a new position, corresponding to the degree of reduction in pressure or to the reduced pressure in pipe 13. The lever 48 may thus be caused to return to any desired position by reducing the pressure of pipe 13 to the desired degree, while in case the pressure in pipe 13 is reduced to its normal degree, the piston means 19 and lever 48 will be returned to their normal positions as will be apparent.

The action of the dash-pot chamber 27, which is always charged with fluid under pressure, and

the cooperative effect of choke 28a, and of the fluid pressure supply choke 89 and of the fluid pressure release choke 104 in causing positive stopping of piston means 19 and lever 48 in any selected position has been described above, as it is understood. Regardless of this description, however, it has been determined that this structure effectively prevents the piston means 19 from overtraveling a position, corresponding to the pressure of fluid in pipe 13, or in other words, the structure assures that the piston means will positively stop and remain in a selective position and thereby accurately position lever 48 according to the pressure of fluid in pipe 13. Moreover, the dash-pot chamber 27 and choke 28a permits the chokes 89 and 104 to be of such size as to provide a change in pressure in the power chamber 23 at a rate which in no way interferes with the desired rate of movement of lever 48 from one position to another position.

It is desired to further point out that the diaphragm 7 and the follower 73 are connected to the other movable parts of the motor, only by the rubber boss 80, and due to the resiliency and relatively small area of this contact the diaphragm and follower 73 are substantially in a floating condition and hence freely adjustable against or by the force of spring 77 relative to said motor parts. Tilting of the diaphragm may therefore be free and relative to the valve member 85 so as to prevent binding of sleeve 98 within said member, or binding of the piston stem 34 within the wear bushing 33. The diaphragm is thus adjustable with a maximum degree of accuracy with respect to changes in pressure of fluid in pipe 13, and the parts controlled by said diaphragm are likewise freely adjustable, thereby providing for correspondingly accurate adjustment of piston means 19 and lever 48 which are forced to assume positions corresponding to the accurately adjusted position of the diaphragm.

When the motor is mounted on an internal combustion engine the vibration of the engine will cause vibration of the diaphragm 7 within the casing as it substantially floats on the end of spring 77. The rubber boss 80 acts however to minimize transfer of such vibration to the sleeve 98, and this is very important, in that it will minimize wear and replacement of operating parts of the structure associated with the piston means 19, and it will also prevent vibration of the valves on their seats and consequent leakage of fluid under pressure past said valves.

In case of failure of the supply of fluid under pressure on an airplane, by way of pipe 13, it is desirable that the different controlling devices or motors on the engine or engines automatically operate to insure continued operation of the engine or engines at an adequate speed to maintain the airplane in the air. The motor above described, and shown in Fig. 1 of the drawings, may be employed for controlling the richness or temperature of the fuel mixture to an engine and in case of loss of the supply of controlling fluid pressure to pipe 13 it is therefore desirable that the controlling lever 48 be automatically moved back to its normal position to provide a rich fuel mixture, or fuel at a temperature which will insure against freezing of moisture in the fuel supply lines.

This automatic return of lever 48 to its normal position is obtained in case of loss of the supply of fluid pressure to control pipe 13 and diaphragm chamber 9 by the force of spring 77. It will be seen that if the pressure of fluid in chamber 9

is lost, the spring 77 will move flange 75 on follower 73 into contact with collar 95 on the valve member 85, which will permit spring 101 to move sleeve 98 out of contact with the release valve 104 so as to open chamber 23 to atmosphere, and spring 77 will then pull the piston means 19 to the position in which the adjusting screw 68 engages the stop shoulder 69 on the power cylinder portion 14, such contact being obtained prior to or at least coincidental with engagement between said diaphragm and stop 83 in the cover 5.

Description and operation Fig. 2

The structure shown in Fig. 2 is particularly adapted for controlling the throttle or speed of an engine such as above referred to, and differs from the structure shown in Fig. 1 mainly in the provision of means for defining a maximum pressure position of lever 48, and of means for automatically positioning said lever intermediate its two extreme positions in case of loss of the supply of controlling fluid, so as to thereby maintain a supply of fuel to the engine which will ensure operation of the engine at a speed sufficient to maintain the airplane in flight.

By referring to my copending application, herebefore referred to, it will be found that I have provided means whereby the pilot of the plane is able to adjust the speed of the several engines in unison, while the engineer is able to adjust the speed of the engines individually, so that if all engines are not operating in synchronism in response to the pilot's control, the engineer may adjust the speed of any individual engine or engines to obtain such synchronism. Now in case the pilot had operated his control device to provide for maximum engine speed, it would be undesirable for the engineer to be able to effect an adjustment to increase the speed of any individual engine, since such an adjustment could result in the breakage of links, etc.

Referring now to the structure shown in Fig. 2 wherein parts like corresponding parts of the motor shown in Fig. 1 of the drawings, are designated by the same reference numerals.

The lever 48 is shown in the minimum engine speed or idling position, and the maximum engine speed position may be such as indicated by a dot and dash line 113. The boss 45 projecting into chamber 25 in the power cylinder position 14 of the motor is provided externally with screw threads upon which is adjustably mounted a stop 114, the inner end of which stop is arranged for contact by piston means 19 when the lever 48 is in its maximum speed position indicated by the dot and dash line 113. This adjustable stop 114 will be adjusted at the motor on all engines on the plane to cause operation of the engines at the same maximum speeds. Thus, if the pilot adjusts the motors to obtain maximum speed of the engines, the engines will operate at maximum speed in synchronism, and the stops 114 in the motors will prevent the engineer from adjusting the motor in the direction to cause an increased speed and thus prevent damage to links or the like which may be used to connect the motors to the fuel governing means on the engines.

The means operative in case of failure of the supply of fluid under pressure to pipe 13 to move the lever 48 to and to then hold it in a position, such as indicated by dot and dash line 115, to provide for operation of the engine at a speed to maintain the airplane in flight will now be described.

In the structure shown in Fig. 2 a casing sec-

tion 116 is employed in place of casing section 1 and differs therefrom in not being provided with the end wall 2 which carries sleeve 3. Interposed between the casing section 116 and the power cylinder portion 14 of the motor is a casing section 117 having an end wall 118 carrying centrally a sleeve like projection 119, said end wall and projection corresponding to the wall 2 and sleeve 3 in the structure shown in Fig. 1, except that the outer surface of projection 119 is cylindrical in form and constitutes one wall of an annular ring-like piston chamber, the other concentric wall of which is provided on the inner surface of the casing section 117. Disposed between these walls is an annular ring-like piston 120 having inner and outer ring grooves in which are mounted packing rings 121 and 122 having sealing and sliding contact with the respective cylinder walls.

The regulating spring 77 bears against one side 20 of piston 120 while at the opposite side of this piston there is a pressure chamber 123 between the piston and end wall 118. Chamber 123 is connected by a passage 124 to a passage 125 which leads to one end of pipe 30 normally supplied with 25 fluid under pressure from the control pipe 13. Passage 124 also provides communication between pipe 30 and passage 29 in the power cylinder portion 14 of the motor to supply fluid under pressure to the latter, as in the structure shown in 30 Fig. 1.

When the control pipe 13 is supplied with fluid under pressure, this pressure will be effective in chamber 123 on piston 120, and the area of said piston is such that this pressure will move said piston to and then hold it in the position in which it is shown in the drawings and which is defined by contact with the end of the casing section 116. In this position spring 77 will be conditioned identically as by contact with wall 2 in the structure 40 shown in Fig. 1.

Upon failure of pressure of fluid in pipe 13 and thereby in chamber 123, the pressure of spring 77 will move the piston 120 in the direction of the left hand to a position which may be defined 45 by engagement with adjusting shims 126 supported by the end wall 118.

The piston means 19 has a stem 127 differing from stem 34 in the structure shown in Fig. 1 of the drawings only in that an annular shoulder 128 is provided adjacent to and just back from the end engaged by collar 86 on the valve member 85. The piston 120 has a sleeve like extension 129 projecting within spring 77 and having adjacent its end sliding and supporting contact on the outer surface of the projection 119 carried by wall 118. At the end of projection 129 is an inturned annular flange 130 provided for contact with shoulder 128 but slightly spaced from said shoulder with the parts of the motor in their normal positions in which they are shown in Fig. 2 of the drawings.

A cover 131 is used with this motor, instead of cover 5, and carries centrally an adjustable stop 132 which extends into diaphragm chamber 9 and which has screw-threaded engagement with said cover for movement either toward or away from the diaphragm. A sealing ring 133 carried by cover 131 and engaging the peripheral surface of stop 132 is provided to prevent leakage of fluid under pressure from chamber 9. A lock nut 134 on stop 132 is provided for contact with the cover to secure said stop in an adjusted position. The stop 132 is adjusted to a position in which it is shown in the drawings and in this position the diaphragm will be out of contact with said stop 75.

when subject to the normal control pipe pressure of 80 pounds. Upon failure of this pressure the diaphragm will be moved by spring 77 into contact with stop 132.

The valve member 85 is provided with a head 135, differing from head 94 in the structure shown in Fig. 1, only in that collar 95 is omitted and a stop shoulder 136 is provided for contact with the diaphragm follower flange 75.

In operation, when the control pipe 13 is charged with fluid at normal pressure, the parts of the motor shown in Fig. 2 will assume the positions in which they are shown in the drawings, and when so positioned, said motor will operate in response to various pressures of fluid in said pipe, above the normal pressure, in the same manner as the structure shown in Fig. 1, and above described.

However in case of failure of the supply of fluid under pressure to pipe 13 the spring 77 will move the piston 120 into contact with shims 126 and, at the same time, will move the diaphragm 7 into contact with stop 132.

In case the engine is operating at a speed in excess of that provided with lever 48 in the position indicated by dot and dash line 115 at the time of failure of the supply of fluid under pressure to pipe 13, the flange 75 on the diaphragm follower 73 will contact shoulder 136 on the valve member 85 and the spring 77, acting through said follower, will then pull the piston means 19 and lever 48 to the intermediate speed position, indicated by the dot and dash line 115, in which position the diaphragm will contact stop 132. At the same time, the movement of piston 120 by spring 77 will move flange 130 toward and into contact with shoulder 128 on the piston stem 127, said contact being obtained with the diaphragm 7 in contact with stop 132 and with said piston engaging shims 126, thereby securing the lever 48 against movement past the intermediate position in the direction of its normal position. The lever 48 will thus be securely held by spring 77 in its mid-position, indicated by dot and dash line 115 against movement in one direction by contact between the follower flange 75 and shoulder 136 on the valve member head 135, and in the opposite direction by contact between the flange 130 on piston 120 and shoulder 128 on the piston stem 127.

Regardless of the position of lever 48 at the time of failure of fluid pressure in pipe 13, the structure will operate to move lever 48 to and then hold it in its position indicated by dot and dash line 115, as will be apparent without further description.

Summary

From the above description it will now be seen that I have provided a fluid motor which is relatively small, compact, light in weight, sensitive to variations in control pressure, positive and accurate in adjustment according to changes in the control pressure, and which is operative automatically in case of failure of the supply of control pressure to automatically cause the device being controlled to assume a predetermined chosen position.

Having now described my invention, what I claim as new and desire to secure by Letters Patent, is:

1. A fluid motor comprising a casing having a fluid pressure control chamber and fluid pressure power chamber, power means in said casing subject to and adjustable in accordance with variations in pressure in said power chamber, valve

means comprising a movable member operable upon axial movement in one direction to supply fluid under pressure to said power chamber and upon movement in the opposite direction to release fluid under pressure from said power chamber, pilot means in said casing comprising a flexible diaphragm arranged in coaxial relation with said movable member, and a resilient boss associated with said diaphragm at its center for contact with said movable member and capable of movement out of such contact, said pilot means being subject to pressure of fluid in said control chamber and operable through said boss upon an increase in such pressure to move said movable member in said one direction, and means operable upon a reduction in pressure of fluid in said control chamber to move said movable member in the opposite direction.

2. A fluid motor comprising a casing having a fluid pressure control chamber and a fluid pressure power chamber, power means in said casing adjustable in accordance with variations in pressure of fluid in said power chamber, valve means carried by said power means comprising a member movable axially of said power means in one direction to effect a supply of fluid under pressure from a pressure chamber in said power means to said power chamber and movable axially of said power means in the opposite direction to effect a release of fluid under pressure from said power chamber, a flexible diaphragm in said casing arranged in coaxial relation with said movable member, an integrally formed resilient projection at the center of said diaphragm arranged to engage said movable member for moving said movable member in said one direction and capable of movement out of contact with said member, said diaphragm being subject to pressure of fluid in said control chamber and operable upon an increase in such pressure to move said movable member in said one direction, and means operable upon a reduction in pressure of fluid in said control chamber to move said movable member in the opposite direction.

3. A fluid motor comprising a casing having a fluid pressure control chamber and a fluid pressure power chamber, power means in said casing subject to and adjustable by pressure of fluid in said power chamber, valve means operable to control pressure of fluid in said power chamber, a regulating spring in said casing, pilot means in said casing subject to pressure of said regulating spring and opposing pressure of fluid in said control chamber and movable relative to said power means upon an increase in pressure in said control chamber to effect operation of said valve means to supply fluid under pressure to said power chamber, said regulating spring means being operable upon a reduction in pressure of fluid in said control chamber to move said pilot means relative to said power means to effect operation of said valve means to release fluid under pressure from said power chamber, and means providing for said movement of said pilot means relative to said power means and operable by said regulating spring means upon loss of fluid under pressure from said control chamber to engage and move said power means to a chosen position.

4. A fluid motor comprising a casing, a pressure responsive power member in said casing having a normal position and being movable therefrom upon supply of fluid under pressure to a power chamber, valve means including a valve control member operable upon movement in one direction

to effect operation of said valve means to supply fluid under pressure to said chamber and upon movement in the opposite direction to effect operation of said valve means to release fluid under pressure from said chamber, pilot means in said casing arranged in coaxial relation to said valve means and valve control member and having a one-way drive connection with said valve control member and operable upon supply of fluid under pressure to a control chamber to effect movement of said valve control member in said one direction, regulating spring means in said casing opposing pressure of fluid on said pilot means and operable upon release of fluid under pressure from said control chamber to move said pilot means in a direction away from said valve control member, release means operable to move said valve control member in said opposite direction upon movement of said pilot means by said regulating spring, and means operable by said regulating spring to move said power member in the direction of its normal position subsequent to operation of said valve means to release fluid under pressure from said power chamber.

5. A fluid motor comprising a casing having an interior wall, a power member in said casing disposed at one side of said wall and cooperating therewith to form a power chamber, said power member having an extension extending through said wall, supply and release valve means including an axially movable control member carried by said extension in coaxial relation therewith and being operable upon movement of said control member in the direction of said power member to supply fluid under pressure to said power chamber and in the opposite direction to release fluid under pressure from said power chamber, a release spring acting on said control member opposing movement thereof in the direction of said power member and operable to move said control member in said opposite direction, a pressure regulating spring, pilot means in said casing arranged in coaxial relation to said control member and subject on one side to pressure of said regulating spring and on the opposite side to pressure of fluid in a control chamber, and being operable against said regulating spring upon supply of fluid under pressure to said control chamber to move said control member in the direction of said power member and being operable by said regulating spring upon release of fluid under pressure from said control chamber to render said release spring operable to move said control member in said opposite direction, and means operable by said regulating spring upon operation of said control member to release fluid under pressure from said power chamber to move said power member.

6. A fluid motor comprising a casing having an interior wall, a power member in said casing disposed at one side of said wall and cooperating therewith to form a power chamber, said power member having an extension extending through said wall, supply and release valve means including an axially movable control member carried by said extension in coaxial relation therewith and being operable upon movement of said control member in the direction of said power member to supply fluid under pressure to said power chamber and in the opposite direction to release fluid under pressure from said power chamber, a release spring acting on said control member opposing movement thereof in the direction of said power member and operable to move said control member in said opposite direction, a pressure reg-

ulating spring, pilot means in said casing arranged in coaxial relation to said control member and subject on one side to pressure of said regulating spring and on the opposite side to pressure of fluid in a control chamber, pressure responsive means in said casing operable by pressure of fluid in a third chamber to compress said regulating spring against said pilot means, said pilot means being operable against said regulating spring upon supply of fluid under pressure to said control chamber to move said control member in the direction of said power means and being operable by said regulating spring upon release of fluid under pressure from said control chamber to render said release spring effective to move said control member in said opposite direction, said pressure responsive means being movable by said regulating spring to a certain position upon loss of fluid under pressure from said third chamber, means operable by said pressure responsive means upon movement to said certain position to urge said power means in a direction to a chosen position, and means operable by said regulating spring upon loss of fluid under pressure from said control chamber and subsequent to operation of said control member to release fluid under pressure from said power chamber to urge said power member in the opposite direction to said chosen position.

30 7. A fluid motor comprising a casing having a power chamber, a control chamber, a dash-pot chamber and a constantly open communication between said control and dash-pot chambers, choke means in said communication adapted to 35 restrict flow of fluid under pressure into and out of said dash-pot chamber, a combined control and fluid pressure supply pipe connected to said control chamber and normally charged with fluid at a pressure in excess of atmospheric pressure, differential area movable power means in said casing having at one side a relatively large area subject to pressure of fluid in said power chamber and having at the opposite side a smaller area subject to pressure of fluid in said dash-pot 40 chamber, pilot means in said casing subject to pressure of fluid in said control chamber, valve means in said casing for controlling the pressure of fluid in said power chamber, means connecting said valve means for control to both 45 said pilot and power means, said pilot means being movable relative to said power means upon an increase in pressure of fluid in said control chamber to effect operation of said valve means to supply fluid under pressure from said pipe to said power chamber and upon a reduction in 50 pressure of fluid in said control chamber to effect operation of said valve means to release fluid under pressure from said power chamber, said power means being movable in one direction by 55 pressure of fluid in said power chamber upon supply of fluid under pressure thereto and being movable in the opposite direction by pressure of fluid in said dash-pot chamber upon release of fluid under pressure from said power chamber, 60 and being movable relative to said pilot means upon cessation of movement of said pilot means, said power means being operable upon movement relative to said pilot means to effect operation of said valve means to bottle the fluid pressure in said power chamber in a position of said power means corresponding to the position of said pilot means.

75 8. A fluid motor comprising a casing, a combined control and fluid pressure supply pipe connected to said casing and normally charged with

19

fluid at a pressure in excess of atmospheric pressure, said casing having a dash-pot chamber and a power chamber and a constantly open communication between said pipe and dash-pot chamber, choke means in said communication arranged to restrict flow of fluid under pressure into and out of said dash-pot chamber, differential area power means in said casing having a relatively large area subject to pressure of fluid in said power chamber and a smaller area subject to pressure of fluid in said dash-pot chamber acting in opposition to pressure of fluid in said power chamber, and means operable upon an increase in pressure of fluid in said pipe to supply fluid under pressure from said pipe to said power chamber and upon a reduction in pressure of fluid in said pipe to release fluid under pressure from said power chamber.

9. A fluid motor comprising a casing having a power chamber, a control chamber and also having a third chamber which is constantly open to a source of fluid under pressure, power means in said casing having a relatively large area subject to pressure of fluid in said power chamber

20

and a smaller area subject to opposing pressure of fluid in said third chamber, valve means in said casing operable to control pressure of fluid in said power chamber, regulating spring means in said casing, pilot means in said casing subject to pressure of fluid in said control chamber and opposing pressure of said spring means and movable relative to said power means upon an increase in pressure in said control chamber to effect operation of said valve means to supply fluid under pressure to said power chamber and movable by said spring means relative to said power means upon a reduction in pressure in said control chamber to effect operation of said valve means to release fluid under pressure from said power chamber, means arranged to limit the extent of movement of said pilot means by said regulating spring means relative to said valve means upon a reduction in pressure of fluid in said control chamber and operable by said spring means upon loss of fluid under pressure from said control chamber to move said power means to a chosen position.
